UNITED STATES PATENT OFFICE.

SIDNEY D. KING, OF DUNMORE, PENNSYLVANIA.

SIDE BEARING FOR RAILWAY-CARS.

SPECIFICATION forming part of Letters Patent No. 630,358, dated August 8, 1899.

Application filed May 31, 1899. Serial No. 718,876. (No model.)

To all whom it may concern:

Be it known that I, SIDNEY D. KING, a citizen of the United States, residing in Dunmore, in the county of Lackawanna, in the State of Pennsylvania, have invented new and useful Improvements in Side Bearings for Railway-Cars, of which the following is a full and correct description.

The invention relates to the provision in a railway-car, in connection with the ordinary bearing-springs, which are sustained upon the outer extremities of the axles of the track-wheels and which at their upper extremity receive the bed-frame of the car, of corresponding auxiliary or supplemental springs which are mounted in housings or casings which are fixed upon the bed-frame and between it and the box or body of the car, such enclosure being commonly termed the "spring-case," the object of this provision being to furnish between the car and the main subjacent body-springs or bearing-springs, which have great rigidity or stiffness and firmness, a means whereby the jar, shock, concussion, and also the twist or torsional strain upon the frame, sides, and roof of the car arising from sudden contact of the wheels with obstructions and also from unevenness or inequalities of surface of road-bed or track-rails, abrupt curves, or from any cause whatever may be modified and alleviated through the distribution or diffusion throughout the superstructure of the car of such disturbing and injurious effects, for it will be understood that the auxiliary springs are of much greater flexibility and compressibility than the main or bearing springs and that by reason of this difference of quality or function they operate through their interposition between the bearing-springs, which first receive and take up or transmit any shock which is imparted to the truck-wheels from below, and the body of the car above to relieve and modify, spread out, or "cushion," as it were, and thereby minimize the jarring and wearing effects which would otherwise result from such shocks. Cars showing this general construction are found in United States Patent No. 249,370, issued to me on the 8th day of November, 1881, and in United States Patent No. 273,693, issued to me on the 6th day of March, 1883. These cars have been employed for several

years with results in most respects, so far as their general mechanical operation is concerned, so satisfactory as to leave little to be desired; but it has been found in numerous instances that upon rough roads and upon tracks which abound in short curves the frequent violent pounding contact of the coils of the springs one upon an other, caused by the up-and-down movement of the body of the car when heavily loaded, has caused gradual disintegration and ultimate destruction through fracture of the body of the springs themselves, thereby rendering their renewal necessary, and this experience has led me to devise the novel and more effective and durable construction which will now be described and claimed.

In the accompanying drawings, which constitute a part of this specification, Figure 1 represents a side perspective elevation of a portion of a railway-car which has my improved spring bearing-case applied upon the top of the truck-frame thereof. Fig. 2 is a detail showing the relation of the spring-case to the body of the car above it. Fig. 3 is a top plan view of the spring-case and of the spring itself in part. Fig. 4 is a side elevation showing the side bearing and its spring. Fig. 5 is a detail bottom plan of the central portion of the casing and represents the inner shoulder, stop, or seat in the top of the dome or main chamber of the casing, the cap and the spring having been removed. Fig. 6 represents an end elevation of the casing or main chamber, the slideable cap and the spring proper having been detached. Fig. 7 is a top plan of the vertically-movable cap detached. Fig. 8 is a bottom plan or interior view of the cap detached. Fig. 9 is a vertical longitudinal section of the cap detached. Fig. 10 is a transverse section of the cap as in the line $y-y$ of Fig. 9. Fig. 11 is a side view of the semi-elliptic spring. Fig. 12 is a top plan of the spring shown in side view in Fig. 11. Fig. 13 is a transverse section as in the line $x-x$ of Fig. 12. Fig. 14 represents in a plan view a modified construction of the dome or main chamber which incloses the spring and within which the spring and the cap which surrounds it have up-and-down movement.

As will be seen in Figs. 1 and 3, the spring-case sc of the side bearing sb is secured by

bolts b^2 b^3 or other suitable means to the upper surface of the truck-frame tf , the projecting unattached extremities of the horizontally-arranged spring s resting loosely between the upwardly-projecting guides g upon the base-plate bp of the spring-case; but it will be apparent that the base-plate, and also the side supports or buttresses ss of the spring-case, might be dispensed with and 10 that the chamber or dome c might be provided with heavy flanges cf , suitably perforated, to permit it to be secured directly to the plate of the truck-frame, substantially as in Fig. 14. Under such modified construction the 15 projecting extremities of the spring would rest directly upon the surface of the truck-frame, or in suitable shallow grooves or guide-ways formed in the body of the frame, to prevent possible lateral deviation of such extremities in their slight movement toward or from the center of the spring-case as the spring is alternately compressed and released.

Upon the bottom of the car A and in vertical plane with the cap c^2 of each spring-case 25 is applied a "rub-iron" or friction-plate a^3 of suitable dimensions. It should be understood that when the car is at rest the rub-iron and the spring-cap are several inches asunder instead of being nearly in contact, as seen in 30 Fig. 2.

To facilitate the movement of the spring-cap toward or away from its seat upon the shoulder sh in the upper extremity of the chamber c , the exterior surface of the cap and 35 the interior surface or spring way of the chamber are uniformly diminished or tapered from bottom to top on each of the four sides of these parts, the chamber having a rectangular top opening o to permit the upper portion 40 of the cap to project through it as the end flanges or shoulders ef of the cap come to rest upon the shoulders sh of the chamber in the manner described.

The spring s is in this instance composed 45 of four loosely-overlying leaves, which are composed of steel and are, at their mid-length, rigidly secured together by an inclosing band or clamp, which is formed from suitable metal and may be termed the "hub" hu . In 50 the upper extremity of the spring-cap at the center thereof is a shallow rectangular cavity ca , Figs. 8, 9, and 10, which is adapted to receive and engage the upwardly-projecting portion of the hub, and thereby prevent any 55 displacement of the spring longitudinally.

It will be noted that the outer extremities of the longer or bottom leaf of the spring are curved first downwardly and then upwardly at the point where the spring rests upon the 60 bottom or base plate of the side bearing, or, when that construction is adopted, upon the top of the truck-frame. By reason of this curvature of the spring it is enabled in its slight longitudinal to-and-fro movement to 65 pass freely over slight inequalities or obstacles in or upon the surface on which it rests instead of striking them by its extreme end

and receiving or causing possible injury through such contact.

Under the construction shown in and in the 70 practical use of the described side bearing the parts are so formed and arranged that the distance between the inner upper extremity of the spring case or chamber c and the bottom thereof is greater than the distance 75 between the top of such spring-case and the rub-iron or friction-plate, upon the car. As a consequence of this difference the spring can never be inoperative and inert, but even when the rub-iron and the spring-case are under any violent movement of the car-body 80 brought for an instant into contact will still exert its relieving upward pressure against the face of the rub-iron and will thereby to the extent of such upward thrust relieve the 85 downward pressure upon the bearing-springs upon the axle, whereas if such distances were equal contact of the rub-iron or friction-plate with the top of the spring case or chamber 90 would flatten the spring against the floor of the chamber, and it would thus become wholly ineffective, and, in the parlance of the shops and "the yard," "dead" and incapable of any active mechanical function whatever. This capability of continuous exertion of its 95 relieving and "cushioning" powers is of the utmost importance in the practical operation of all the various classes of cars to which the invention is applicable.

An additional important advantage in the 100 practical use of this invention results from the facility with which the described side bearing may be substituted for others which are less effective in their operation or which have become greatly worn or which for any 105 other reason it is desired to discard. Furthermore, it will be seen that in the use of this invention in cases in which it is desired to renew the side bearing by the substitution of a new spring only the operation may be 110 accomplished by the removal of the spring alone. A pivoted recessed lifting-ring r or any simple equivalent thereof being provided upon the top of the spring-cap, the cap is, by means of such ring, lifted to its highest position in contact with the shoulders or seat sh 115 at the upper extremity of the spring chamber or way. This effects disengagement of the hub or band hu at the mid-length of the spring from the cavity ca in the spring-cap, by which the centrality and undetachability 120 of the spring would otherwise be maintained, whereupon the spring may readily upon slight compression be moved longitudinally along its ways, and being thus withdrawn in either direction a new one is as readily substituted. The ability thus to substitute a new spring 125 for an old one in a moment of time is another important practical advantage arising from this construction, economy of time being an 130 important factor in all railway operations.

In the foregoing description provision is made in the case or chamber for a rectangular cap and a rectangular opening only; but

it will be apparent that each might be made of circular, elliptical, or other convenient form without at all exceeding the limits of this invention; also, the case or chamber 5 might in some cases be made long enough to wholly inclose the arch-like spring.

The invention having been thus described, what is claimed is—

1. A side bearing for railway-cars which is 10 provided with a spring case or chamber which is open at its bottom and at its ends, and which, interiorly, is upwardly-tapered or diminished from its lower extremity; a horizontally-arranged spring which rests by its ends 15 upon the base-plate of the chamber, or upon the truck-frame; and an upwardly-tapered cap; which rests upon the horizontally-arranged spring; the case or chamber being adapted to permit the spring-sustained cap 20 to project upwardly through it; substantially as and for the purposes set forth.

2. A side bearing for railway-cars which has a spring case or chamber which in its upper extremity is provided with an opening; 25 a spring, within the case or chamber; and a spring-cap or rub-plate which is sustained upon and actuated by the spring, and is adapted, in the operation of the side bearing, to project through the opening in the case or 30 chamber, and to receive the contact of the friction-plate or "rub-iron" of the car upon which such side bearing is mounted.

3. A side bearing for railway-cars which is provided with a spring case or chamber which 35 is open at its bottom and at its ends; a spring-cap which is movable, up or down, within the spring case or chamber which is insertible and withdrawable through the end openings of such case or chamber; and a relieving- 40 spring which by its central portion supports the spring-cap, and which by its ends rests upon the base-plate, or other surface, upon which the side bearing is mounted.

4. A side bearing for railway-cars which 45 embraces a base-plate which rests upon, or is formed by, the body of the truck-frame; a spring case or chamber which is open at each end, and is secured upon the base-plate; an arch-like or semi-elliptic horizontally insertible and withdrawable spring, within the case 50 or chamber, and resting by its ends loosely and unattached, upon the base-plate; and a vertically-movable cap, which rests, by its central portion, upon the arch-like spring; 55 and which, in the operation of the side bearing, alternately actuates and is actuated by the spring.

5. In a side bearing for railway-cars, a spring case or chamber which is open at its 60 top, at its bottom, and at its ends; a horizontally-arranged arch-like, or semi-elliptic, detachable spring which is centrally placed within the case or chamber, and which rests

by its extremities upon the plate on which the side bearing is mounted; and a spring- 65 cap which is movable, up or down, within the case or chamber, through a space which is greater in extent than the distance between the top of the case or chamber, and the bottom of the "rub-iron" or friction-plate upon 70 the car.

6. In a side bearing for railway-cars, a spring case or chamber which is mounted upon a base-plate, and which is open at each of its two ends, at its bottom and at its top; 75 an arch-shaped spring which is received within the case or chamber and is horizontally withdrawable therefrom, and which by each extremity of the arch rests upon the base or supporting plate; and a cap which rests upon 80 the crown of the arch-shaped spring, and which is movable, up or down, within the case or chamber, according as it is actuated by the pressure of the spring from below, or by downward movement of the car-body and its fric- 85 tion-plate or "rub-iron" from above.

7. A side bearing for railway-cars which has a horizontally-arranged spring case or chamber; a slidable spring-cap or rub-plate; and a horizontally-arranged arch-like or semi- 90 elliptic relieving-spring which is detachably centered in the slidable spring-cap; the case or chamber being open at each end, so that the horizontally-arranged spring may be withdrawn, for repair or renewal, without removal 95 of any other of the parts of such side bearing.

8. A side bearing for railway-cars which embraces a spring case or chamber which is open at its two opposite ends, at its bottom and at its top, and which rests, either indirectly by a base-plate, or directly, upon the truck-frame of the car; a vertically-movable cap, within the spring case or chamber; and a horizontally-arranged spring which is loosely engaged with the movable cap, and 105 which is readily withdrawable horizontally endwise from the spring case or chamber.

9. A side bearing for railway-cars which is provided with a spring case or chamber, and with an arch-shaped spring which rests loosely 110 and unattached, by its opposite extremities, upon a horizontally-arranged bed-plate, or truck-frame and which is insertible into, or withdrawable from its operative position, without removing any of the other parts of 115 the construction; substantially as and for the purposes set forth.

In testimony whereof I have hereunto, at Dunmore, Pennsylvania, on this 17th day of May, 1899, affixed my signature in presence 120 of two subscribing witnesses.

SIDNEY D. KING.
